WORK CONVEYING BOX FOR SEWING-MACHINE TABLES

Daniel J. Hogan, Ashley, Pa., assignor to Harris-Hogan Company, a corporation of Pennsylvania

Application September 27, 1946, Serial No. 699,890

5 Claims. (Cl. 311—13)

1

This invention relates to factory practice and is more particularly directed to apparatus for facilitating the handling of various articles of manufacture where these articles are to have different operations performed thereon at a number of different stations.

In the present embodiment, the invention has been illustrated in connection with the handling of fabric materials such as garments and the like, although of course I do not intend to limit the invention in this respect since it should be understood that the apparatus here shown and described is capable of being used in a number of different environments.

In garment factories it is common practice today to provide a row or bank of sewing machines with the operator at each machine performing a different kind of sewing operation or the sewing of different portions of the garment.

It is customary to arrange the sewing machines in a row so that after the sewing operation has been done by the operator of the first machine, the material is collected as it leaves the machine and is then transported to the operator of the second machine who performs the necessary operation and then the material is passed on successively to the other machines in the row until the sewing operation has been completed.

The transfer of material from one machine in a row to the other has entailed considerable loss in time as well as the necessity of employing someone to carry out the transfer operation.

The present invention is designed to facilitate transfer of the material being operated upon from one machine to the other and to accomplish this in such a manner that it can be rapidly done by the operator of the machine without the necessity of leaving the operating station, thereby eliminating the employment of persons whose duty it is to transport the material from machine to machine.

It is believed that the advantages of the present construction will be obvious from a reading of the accompanying description taken in connection with the attached drawings, it being understood that there is illustrated only the preferred embodiment of the present invention and that changes in proportions and other minor details may be resorted to so long as they fall within the spirit and scope of the appended claims.

Referring to the drawings:

Fig. 1 is a diagrammatical plan view of one arrangement of sewing machines and conveying boxes forming the subject matter of the present invention.

Fig. 2 is a diagrammatical plan view of another arrangement of sewing machine tables and conveying boxes.

Fig. 3 is a perspective view of the conveying box itself, and

2

Fig. 4 is a fragmentary sectional view taken along the line 4—4 of Fig. 1 showing the relation and relative elevation of the box and sewing machine table.

Describing the invention more in detail, there is shown a sewing machine table at 10 provided with a sewing machine 11 and the operator's seat is shown at 12.

It is to be noted that the operator's station and the sewing machine are located toward one end of the table 10 so that a relatively large apron 13 is provided at one side of the sewing machine upon which the garments or fabric may be spread by the operator of the machine to facilitate the sewing operation.

In Fig. 1 the sewing machine tables are illustrated as being arranged in two rows and with the tables in each row aligned transversely so that a compact arrangement is provided to economize on available space.

In order that the material being operated upon may be passed with facility from one table to the other in each row, there is provided a work conveying box or receptacle 14 which is here shown as being substantially L-shaped with the leg portion being indicated at 15 and the foot portion as at 16.

As clearly shown in Fig. 1 the conveying boxes are arranged between the tables in each row with the foot portion having one wall parallel with the rear edge of the table and being of sufficient length to extend from one end of the table to a location in back of the machine and the leg portion 15 is of such length as to extend from one table to the other.

By means of this arrangement it will be seen that the material passing through the first sewing machine indicated in Fig. 1 as machine A will be deposited in the foot portion 16 of the first box. As the material is fed through the first machine and is deposited in the foot portion 16 of the first box, it engages the inclined wall 17 and is gradually urged toward the left or into the leg portion 15 of the box as shown in Fig. 1.

As the material accumulates in the box the various layers of articles being operated upon become entangled or interlaced so that the operator of the second sewing machine indicated at B in Fig. 1 has merely to reach into the leg portion 15 of the box and pull the material toward the second table. Therefore it is obvious that the operator of succeeding machines may easily and quickly move the material from the preceding machine without the necessity of leaving the operating station and without the use of any additional help.

The leg portion 15 of the box is similarly provided with an inclined wall 18 which places the narrow end of the leg 16 adjacent the second table, thereby affording ample room for the op-

erator to move or swing about from the operating station in order to grasp the material in the box and pull it toward the sewing machine table.

As shown in Fig. 1 the material goes from box to table down the first row. At the end of the row it is transferred to the box of the second row and then returns to the end table which is here indicated as C and thence into the end box at which time the sewing operation is complete.

It is to be noted in Fig. 1 that the boxes are arranged so that the leg portion in the first row substantially abuts the leg portion of the boxes in the second row, but that the boxes are arranged in reverse direction.

By means of such construction it will be seen that a very compact arrangement may be had which conserves considerable space and that the material may be rapidly and easily fed to the various operating stations.

In Fig. 2 the arrangement is quite similar to that shown in Fig. 1 except that in this instance only a single row of tables and boxes is disclosed. However, the operation is the same and it is to be understood that since the boxes are portable, they may be moved at will and that any number of a variety of arrangements may be had including any desirable number of boxes and tables in order to handle the particular sewing job that is being taken up at any given time.

Fig. 3 discloses the detailed construction of the box which is provided with side, end, and bottom walls and the box is supported by means of suitable legs here disclosed as consisting of U-shaped angle iron members 19, 20, and 21. The upper ends of the U-shaped legs are suitably secured to the sides of the boxes, it being noted that the leg 20 is secured to the box at the juncture between the leg portion 15 and the foot portion 16. In Fig. 4 the relative height of the table and box is shown, it being preferable that the box be slightly lower than the table in order that the work W may be easily fed into the open upper end of the foot portion 16 of the box.

It is believed that the operation will be clearly apparent from what has been said. The goods to be operated on are deposited in the first box indicated at the lower end of Fig. 1 or Fig. 2. The operator located at the station 12 reaches into the box and moves the material toward the table 10. After passing the material through the first sewing machine 11 the material is fed into the foot portion 16 of the second box and from there is moved by the operator of the second machine toward that table. This operation continues throughout the length of the row. If there are not many operations to be performed, the garment may be completed by the time it reaches the end of the first row. If not, the material may be transferred from the end of the first row transversely to the second row and the material then passed through the second row of machines in the same manner as in the first row until the sewing operation is completed.

The work conveying box may be provided with a beaded upper edge 22 in order that there will be no danger of the material being operated upon engaging the raw edges of the box and thereby interfering with the movement of the material into the same.

I claim:

1. The combination with a plurality of spaced sewing machine tables arranged in a row and having sewing machines thereon arranged to cause the operators thereof to face in the same direction, of a work conveying box provided with

bottom, side, and end walls and an open top, said box being positioned between the tables and having one portion between the rear of the table and the next adjacent operator to receive material passing from one sewing machine and having another portion extending to one side of said next adjacent operator and to the next adjacent table in said row.

2. The combination with a plurality of spaced sewing machine tables arranged in a row and having sewing machines thereon arranged to cause the operators thereof to face in the same direction, and a work conveying box provided with bottom, side, and end walls and an open top, said box being positioned between the tables in the row and having one portion extending parallel to the rear edge of one table between the rear of the table and the next adjacent operator and positioned to receive material passing from the sewing machine of that table and another portion at an angle to the first named portion and extending to one side of said next adjacent operator and to the next adjacent table in said row.

3. A work conveying box comprising a foot portion and a leg portion constituting in effect an L-shaped box having bottom, side, and end walls and an open top, and legs supporting said box, said legs being secured to the box at opposite ends thereof and an intermediate leg secured at the juncture between the leg and foot portions of the box.

4. A work conveying box comprising a foot portion and a leg portion constituting in effect an L-shaped box provided with bottom, vertical end, and front and rear side walls and an open top; the rear side walls of said box converging toward the front walls from the juncture of the leg and foot portions to the opposite ends of the box.

5. A work conveying device comprising a substantially L-shaped box consisting of a foot portion and a leg portion, said portions being composed of bottom, front and rear side walls, and end walls, one of the rear side walls of the foot portion converging from the point of juncture of the foot and leg portions toward the front wall.
